ROUNDING MACHINE

Frederic E. Bertrand, Lynn, Mass., assignor to
 United Shoe Machinery Corporation, Paterson,
 N. J., a corporation of New Jersey

Application February 10, 1937, Serial No. 125,075

20 Claims. (Cl. 12—17)

My invention relates to machines for cutting the periphery of an article to a chosen form, it being particularly concerned with the imparting this form to a portion only of such an article as the insole of a shoe.

There is a commercial insole upon which a lasting rib is produced by so rounding a blank that it has a marginal extension beyond that of the finished insole; splitting or channeling the edge of this insole-piece to divide a lip from a thicker body-portion; trimming or rounding this body-portion to the final form of the periphery of the insole; and finally folding the thinner lip inwardly upon itself and upon the feather, it being secured by cement and furnishing the lasting rib. This invention has as an object the provision of a machine by which the rounding of the body-portion of the margin of an article of the character of that just indicated may be performed accurately, without severing or weakening the lip or like portion which has been divided therefrom.

The above object I attain by combining with a knife movable about an article divided at its edge and which cuts completely through one of the divided portions toward the adjacent face of the other divided portions, guard means for preventing the knife from cutting said other divided portion. Preferably, the sole or other work-piece rests against or contacts with an abutment having co-operating with it a pattern by which a knife and knife-carrier are guided in their operating movement, together with means, as a deflecting member, mounted upon the carrier and extending between a portion of the work and the abutment, which means moves such portion of the work into the field of action of the knife. This causes the knife to make its cut in the work-portion without being unduly close to another portion upon which it is not to operate. By varying the position of the deflecting member along the knife, the depth to which said knife operates may be controlled. In the application of the invention to the rounding of edge-channelled work-pieces, as insoles, the work-controlling member, which may be considered as a plow, extends into the channel in proximity to the point of the knife, there being a surface by which the material at one side of the channel is deflected from the point of the knife along its cutting edge. By this arrangement, the margin of the body-portion of the channelled material may be fully severed, while the lip-portion is held so spaced from the knife that the knife-point will not penetrate it. By providing the plow with a

shank which may be adjustably clamped in the knife-carrier, the depth of action of the knife upon the deflected material may be varied. Without reference to the particular operation which is performed by my improved rounding machine, the work-piece may be located with respect to the pattern by forming the abutment as a gage with a contour corresponding to that of said work-piece. Then, when the work is applied to the gage for clamping with the co-operating pattern, its registration with the periphery of said gage will produce the desired relation to the pattern, and the line of severance of the body-portion of the channelled margin will be correct.

In the accompanying drawing.

Fig. 1 illustrates a particular form of my invention in perspective;

Fig. 2 is a broken, transverse, sectional detail taken just at the rear of and looking toward the knife;

Fig. 3, an enlarged fragmentary plan view, including the knife in section, the plow and a portion of the work, and

Fig. 4, an enlarged detail in front elevation of the knife and plow.

This invention may be made a part of the sole-rounding machine disclosed in Letters Patent of the United States No. 2,057,665, Bertrand, October 20, 1936. For present purposes, only the upper knife disclosed in the patent is used, this being shown at 10, while what in the patented machine is a lower pattern, becomes an abutment or work-supporting gage 12, against which the work positioned by it is pressed by the pattern 14. To permit the abutment to perform its gaging function, its contour is substantially the same as that of the rounded work-piece which is applied to it. If, when the piece is laid upon the abutment, its edge is brought into registration with the abutment-edge, it will bear a definite relation to the periphery of the pattern. Therefore, the cut made by the knife will be properly located. This pattern 14 at its periphery guides the knife 10 and its carrier 16. As usual in machines of this type, the carrier is pivoted at 18 upon an arm 20 to which is imparted a compound movement of oscillation and bodily travel, which causes the knife to move about the pattern under the guidance of its periphery.

It will be assumed that an insole 1 of the character previously mentioned comes to the apparatus with its forepart, which is all that herein need be considered, split or channelled at a in its edge to form a relatively thin marginal lip b, which is to be folded upon itself to furnish a last-

ing rib, and a thicker marginal body-portion *c*, to which this rib is to be secured. The work-piece has been rounded, so the periphery of the fore-part is substantially of the contour desired for the edge of the lip *b*. The periphery of the abutment *12* is also of this form. There must be an excess of width of the margin of the lip-portion over that of the body-portion to provide for its folding, and it is the purpose of my invention to remove from the body-portion a width corresponding to this excess, thus bringing said body-portion to substantially its final form. At the same time, the lip is to be guarded against injury by the knife *10*. Formed vertically in the block *16* in advance of the knife is a groove *22* to receive the shank *24* of a plow or deflecting member *26*. Extending horizontally substantially at right-angles to the shank is an arm *28*, from which the blade of the plow projects. The under face *30* of the plow is preferably horizontal, while the upper face *32* is inclined downwardly toward the pattern and forwardly in the direction of advance of the knife. It is of such thickness that an insole may be applied to it with the lip *b* resting upon the abutment *12* below the surface *30*, while the body-portion *c* is deflected upwardly by the surface *32*. The point of the knife lies near the rear edge *34* of the plow just outside its inner edge *36* and, as is clearly shown in Fig. 4, is located vertically in a plane between the lower surface *30* and the upper surface *32*. To allow this vertical position to be accurately determined, the shank *24* of the plow is secured for adjustment in the groove *22*. The shank and plow may be shifted to the proper height by a screw *38* threaded into a projection from the block *16* with its head in a depression in the shank. Said shank is guided and secured in the adjusted position by a screw *40* threaded into the block and passing through a vertical slot *42* in the shank.

The operator places an insole *I*, divided as previously described into a lip-portion *b* and a body-portion *c*, lip-side down upon the supporting abutment *12*, gaging it thereby with respect to the pattern *14* by bringing the periphery of the insole into registration with that of the abutment. The knife *10* is initially near one end of the breast-line of the sole. In thus positioning the work, the forward edge *44* of the plow *26* is caused to enter the breast-end of the channel *a*. The work is then clamped by the pattern *14* upon the abutment. The inner vertical face of the knife is held against the pattern by an unillustrated spring acting upon the arm *28*. When the apparatus is started in operation, as the plow *26* travels forward, its surface *30* holds the lip *b* down, while the inclined surface *32* deflects the marginal body-portion *c* upwardly into the path of the advancing knife *10*. In this upward deflection of the body-portion *c*, its lower surface is raised from the upper surface of the lip *b*, with which it has been in engagement. This elevation, which is illustrated in Fig. 1 of the drawing, occurs because, as appears in Fig. 4, the face *32* of the plow which travels beneath and in contact with the lower surface of the portion *c*, is inclined upwardly and rearwardly with respect to such travel, so the portion *c* is lifted by an amount equal to at least the difference in height of the plow-surface *32* between its forward and rear edges. The knife *10*, as best shown in Fig. 4, has a cutting edge which extends upwardly from its lowest point to a point above the maximum height of the plow-surface *32*. The location of the knife is beside the plow, with its point below

the surface *32*. It will be seen that the body-portion *c* is deflected upwardly by the plow-surface *32*; that the cutting edge of the knife extends upwardly adjacent to such surface, succeeding points of the portion *c* and succeeding points of the knife-edge occupying together different horizontal planes; and that the deflection and cutting action occur simultaneously. Therefore, the material being severed is shifted upwardly along and in contact with the cutting edge, starting just above the level of the upper surface of the lip *b* and ending its upward deflection near the level of the upper extremity of the surface *32* and near the upper extremity of the cutting edge of the knife. The body-portion *c* is thereby severed about the forepart of the insole to the opposite extremity of the breast-line. There is thus removed a waste strip *d*, leaving a narrower body-portion having the contour of the pattern *14* and of the finished insole. The lip is held positively upon the abutment *12* by the plow, which so guards it against contact with the knife that it remains unaffected, although the body-portion is fully cut. The work-piece, when removed from the apparatus, is ready for the folding of the lip to furnish a lasting rib.

Having described my invention, what I claim as new and desire to secure by Letters Patent of the United States is:

1. In a machine for rounding one portion only of the divided edge of an article, a rounding knife movable about the article and arranged to cut completely through one of the divided portions between its opposite faces and toward the adjacent face of the other divided portion, and means movable with the knife for preventing said knife from cutting said other divided portion.

2. In a rounding machine, an abutment with which the work contacts, a pattern co-operating with the abutment, a knife and its carrier movable under the guidance of the pattern, and means for moving a portion of the work into the field of action of the knife.

3. In a rounding machine, an abutment against which the work rests, a pattern co-operating with the abutment, said abutment furnishing a gage whereby the work may be positioned with respect to the pattern, a knife and its carrier movable under the guidance of the pattern, and a guard member mounted upon the carrier and extending between a portion of the work and the abutment.

4. In a rounding machine, an abutment against which the work rests, a pattern co-operating with the abutment, a knife and its carrier movable under the guidance of the pattern, and a guard member mounted upon the carrier and extending between a portion of the work and the abutment.

5. In a rounding machine, an abutment against which the work rests, a pattern co-operating with the abutment, a knife and its carrier movable under the guidance of the pattern, the knife having an extended cutting edge, and a deflecting member mounted upon the carrier and arranged to shift a portion of the material along the cutting edge of the knife.

6. In a rounding machine, an abutment against which the work rests, a pattern co-operating with the abutment, a knife and its carrier movable under the guidance of the pattern, the knife having an extended cutting edge, a deflecting member mounted upon the carrier and arranged to shift a portion of the material along the cutting edge of the knife, and means arranged to vary the height of the cutting edge.

- the position of the deflecting member along the knife.
7. In a machine for rounding a work-piece having a channeled edge, a pattern against which the work is clamped, a knife and its carrier movable under the guidance of the pattern, and a member mounted upon the carrier and extending into the channel in proximity to the point of the knife.
- 10 8. In a machine for rounding a work-piece having a channeled edge, a pattern against which the work is clamped, a knife and its carrier movable under the guidance of the pattern, the knife having an extended cutting edge, and a member mounted upon the carrier and extending into the channel in proximity to the point of the knife, said member having a surface for deflecting the work at one side of the channel along the cutting edge of the knife.
- 20 9. In a machine for rounding a work-piece having a channeled edge, a pattern against which the work is clamped, a knife and its carrier movable under the guidance of the pattern, and a plow extending into the channel and co-operating with the knife, said plow at the side toward the pattern having a surface inclined from the pattern and forwardly in the direction of advance of the knife.
- 30 10. In a machine for rounding a work-piece having a channeled edge, a pattern against which the work is clamped, a knife and its carrier movable under the guidance of the pattern, and a plow extending into the channel and co-operating with the knife, said plow at the side toward the pattern having a surface inclined from the pattern and forwardly in the direction of advance of the knife and being arranged to elevate the material contacting with it above the point of the knife.
- 40 11. In a machine for rounding a work-piece having a channeled edge, a pattern against which the work is clamped, a knife and its carrier movable under the guidance of the pattern, a plow extending into the channel and co-operating with the knife, said plow at the side toward the pattern having a surface inclined from the pattern and forwardly in the direction of advance of the knife and being arranged to elevate the material contacting with it above the point of the knife, and means arranged to vary the relation of the work-contacting surface to the point of the knife.
- 50 12. In a machine for rounding an insole which has been edge-channeled to separate a lip from the body-portion, a pattern against which a face of the body-portion of the insole is clamped, a knife and its carrier movable under the guidance of the pattern to round the body-portion of the insole, and a plow provided with a shank fixed in the carrier and a blade extending into the channel.
- 60 13. In a machine for rounding an insole which has been edge-channeled to separate a lip from the body-portion, a pattern against which a face of the body-portion rests, an abutment corresponding to the form of the insole to be rounded for gaging the work with respect to the pattern, the pattern and abutment co-operating to clamp the work, a knife and its carrier movable under the guidance of the pattern to round the body-portion of the insole, and a plow mounted upon the carrier and provided with a blade extending into the channel.
14. In a machine for rounding an insole which has been edge-channeled to separate a lip from the body-portion, a pattern against which a face of the body-portion of the insole is clamped, a knife and its carrier movable under the guidance of the pattern to round the body-portion of the insole, a plow provided with a shank fixed in the carrier and a blade extending into the channel, and means arranged to clamp the shank of the plow in different positions upon the carrier.
15. In a machine for rounding an insole which has been edge-channeled to separate a lip from the body-portion, a pattern against which a face of the body-portion of the insole is clamped, a knife and its carrier movable under the guidance of the pattern to round the body-portion of the insole, and a plow provided with a shank fixed in the carrier and a blade extending into the channel, said blade having a surface against which rests the body-portion which has been separated by the channel, which surface is inclined downwardly in the direction of knife-advance.
- 20 16. In a machine for rounding an insole which has been edge-channeled to separate a lip from the body-portion, a pattern against which a face of the body-portion of the insole is clamped, a knife and its carrier movable under the guidance of the pattern to round the body-portion of the insole, and a plow provided with a shank fixed in the carrier and a blade extending into the channel, the point of the knife lying adjacent to the edge of the plow-blade between the body-contacting and lip-contacting faces.
- 25 17. In a rounding machine, a pattern and a gage between which a work-piece is clamped for a rounding operation, the gage having a contour corresponding to that of the work-piece whereby said piece may be located with respect to the pattern, and a movable rounding knife guided by the pattern.
- 30 18. In a rounding machine, a pattern and a gage between which a work-piece is clamped for a rounding operation, the gage having a contour corresponding to that of the work-piece whereby said piece may be located with respect to the pattern, a movable rounding knife guided by the pattern, and a work-guard traveling with the knife.
- 35 19. In a machine for rounding an insole having a channeled edge dividing it into a marginal body-portion and a marginal lip, a work-supporting gage corresponding in contour to the channeled insole, a pattern co-operating with the gage to clamp the insole between them, said pattern having the contour to which the body-portion is to be rounded, and a rounding knife acting to sever the body-portion under the guidance of the pattern.
- 40 20. In a machine for rounding an insole having a channeled edge dividing it into a marginal body-portion and a marginal lip, a work-supporting gage corresponding in contour to the channeled insole, a pattern co-operating with the gage to clamp the insole between them, said pattern having the contour to which the body-portion is to be rounded, a rounding knife acting to sever the body-portion under the guidance of the pattern, and a guard for the lip extending into the channel and co-operating with the knife.
